UNITED STATES PATENT OFFICE.

B D HAYS, OF FORT WORTH, TEXAS.

ТИЛТИНГ КАРРИЕР.

Application filed May 10, 1927. Serial No. 190,224.

My invention relates to package carriers for use on vehicles and other devices and more particularly to tilting carriers; and the object is to provide a simple attachment to 5 be mounted on vehicles of various types which is composed of a rigid member for attaching or mounting the attachment and a tilting member carried by the rigid member for carrying bottles and jars and the like 10 for containing liquids and to means for holding the bottles and jars safely on the vehicle. Other objects and advantages will be fully explained in the following description and the invention will be more particularly pointed out in the claims.

Reference is had to the accompanying drawings which form a part of this application.

Fig. 1 illustrates the carrier as attached to 20 the running board of a vehicle and showing a jar supported thereon.

Fig. 2 is a perspective view, showing the tilting member folded down on the rigid member.

Fig. 3 is a perspective view showing the tilting member opened outwardly.

Fig. 4 is a longitudinal section substantially on the line 4—4 of Fig. 3.

Similar characters of reference are used 30 to indicate the same parts throughout the several views.

The devices herein shown are constructed of thin bar steel. The bars 1 and 2 run parallel to the running board of a vehicle. Bars 35 3 and 4 are transversely arranged relative to the running board and are clamped thereon by hooks or clamps 5 and set screws 7. The bars 1 and 2 are riveted to the bars 3 and 4. The bar 2 is bent at the ends to form up- 40 turned lugs 10. The bottle or other package is supported on a supplemental frame composed of diagonal members 8 and 9 which are bent one-quarter turns at the ends and pivotally connected to lugs 10. The bars 45 8 and 9 are held in their relative positions to each other by riveting the same together at 11. The rivet 12 serves another purpose or function. The rivet 12 has a head spaced from the bar 8 and forms a retaining device for the supplemental frame.

The supplemental frame is locked to the main frame by a bar 13. This bar 13 is 50 slidably mounted on the bars 3 and 4 and held thereon by bolt heads 15, the bolts projecting through slots in the bar 13. The locking bar 13 has an opening 16 large enough to re-

ceive the head 12 and a narrow slot leading therefrom. A handle 14 is formed on the bar 13. The bar 13 is positioned (when the supplemental frame is to be locked thereto) 60 so that head 12 will pass down through the bar. The bar 13 is then moved to bring the slot 16 over the head 12. The supplemental frame will be held securely in place on the rigid frame. When the supplemental frame is to be released for tilting purposes, the bar 13 is moved longitudinally to bring the large part of the slot 16 about the locking bolt 12. The supplemental frame can then be tilted. Thus a bottle or jar can be 70 strapped to the supplemental frame and locked in upright position. When the bottle or jar is to be tilted, release the locking bar 13 therefrom. Retaining loops 21 are attached to the members 8 and 9 and straps 20 are used to attach the bottle or jar to the supplemental frame. The straps 20 may engage a ring 26 which is placed about the bottle. The bottle or jar can be tilted without detaching the same from the supplemental frame and the supplemental frame can be tilted far enough to pour out the 75 contents of the bottle. It is apparent that the straps 20 can be released and the bottle or jar tilted without releasing the supplemental frame from the main or rigid frame. It is more convenient to release the supplemental frame for tilting the bottle. Rubber or other pads 17 may be attached at various 80 parts of the frame members to prevent rattling.

It is apparent that the carrier herein set forth can be used more generally for transporting any kind of packages, boxes, jars or bottles and one of the advantages is that the tilting member can be quickly detached by means shown in the drawings for convenience in handling the tilting member for repacking or refilling or for storing at night without removing the rigid frame which is attached to the vehicle. Lugs 24 are rigid with the ends 25 of bars 8 and 9 and project loosely through lugs 10 which may be easily sprung on and off.

As a supplemental means for preventing the rattling of the tilting member, a strap 18 may be attached to the rigid frame and caught on the bottle, jar, or other package to hold the same firmly. This strap is easily removable when the bottle or other device is 100 to be tilted by the tilting frame, or when the tilting frame is removed.

What I claim is:—

1. A tilting carrier comprising a rigid frame, a tilting frame pivotally connected to one edge of said rigid frame and normally lying thereon, a headed bolt rigid with said tilting frame and depending therefrom, and a locking bar slidably mounted on and connected to said rigid frame and provided with a slot to receive said headed bolt for locking said tilting frame to said rigid frame.
2. A tilting carrier comprising a rigid frame, a tilting frame pivotally connected to one edge of said rigid frame and normally lying thereon and provided with a headed lug depending therefrom, a locking bar slidably mounted on said rigid frame and provided with a slot having a wide portion to receive said lug and a narrow portion for locking said lug for detachably locking said tilting frame to said rigid frame, and loops carried by said tilting frame for use in strapping a bottle or other package to said tilting frame.
3. A tilting carrier comprising a rigid frame provided with upstanding lugs on one side, a tilting frame provided with diagonal members riveted together and pivotally connected to said upstanding lugs, a locking bar slidably mounted on said rigid frame and provided with a locking slot, a headed lug

depending from said tilting frame adapted to enter said slot for detachably locking said tilting frame to said rigid frame, loops rigid with said tilting frame, and straps engaging said loops for attaching a bottle to said tilting frame.

4. A tilting carrier comprising a rigid frame provided with upstanding lugs on one side, a tilting frame pivotally and detachably connected to said lugs, means for detachably locking said tilting frame to said rigid frame in operative position, straps for securing bottles and other packages to said tilting frame, and means for preventing rattling of said frames and the package on said tilting frame including a strap attached to said rigid frame and to the package.

5. A tilting carrier comprising a rigid frame, a tilting frame pivotally and detachably connected to one edge of said rigid frame, pads between said frames for preventing rattling, means for detachably locking said tilting frame to said rigid frame in operative position, means for securing bottles or other packages to said tilting frame, and a strap for attaching said bottles or packages to said rigid frame.

In testimony whereof, I set my hand, this 5th day of May, 1927.

B D HAYS.
